UNITED STATES PATENT OFFICE.

JAMES A. DAWLEY, OF DENVER, COLORADO.

DESIGN FOR A PIN OR BADGE.

SPECIFICATION forming part of Design No. 21,223, dated December 8, 1891.

Application filed September 19, 1891. Serial No. 406,261. Term of patent 3½ years.

To all whom it may concern:

Be it known that I, JAMES A. DAWLEY, a citizen of the United States, residing at Denver, in the county of Arapahoe and State of Colorado, have invented and produced a new and original Design for Pins and Badges, of which the following is a specification, reference being had to the accompanying drawing, forming a part thereof.

10 The drawing is a front view of a pin or badge, showing my design.

The leading feature of my design is a log of wood 1 and a dove 3, with a palm branch in its mouth, sitting upon the same, and a wedge

4 suspended from the center of the log. Suspended from the log by two chains is a circle, upon which are inscribed nine stars 5. Within this is an inner circle, on which is a figure of a palm-tree 6. Back of the two circles are a beetle 7 and an ax 8 crossed.

What I claim is—

The design for a pin or badge herein shown and described.

JAMES A. DAWLEY.
